UNITED STATES PATENT OFFICE.

FRED E. WEAVER, OF LOS ANGELES, CALIFORNIA, ASSIGNOR OF ONE-HALF TO ETHEL O. WEAVER, OF WATTS, CALIFORNIA.

MOTION-PICTURE APPARATUS.

1,367,109.

Specification of Letters Patent.

Patented Feb. 1, 1921.

Application filed November 22, 1919. Serial No. 338,974.

To all whom it may concern

Be it known that I, FRED E. WEAVER, a citizen of the United States, residing at Los Angeles, in the county of Los Angeles and 5 State of California, have invented new and useful Improvements in Motion-Picture Apparatus, of which the following is a specification.

This invention relates to motion picture apparatus and more particularly to means for automatically stopping the display of pictures from one projecting apparatus and at the same time starting the display of pictures in another projecting apparatus so 15 that there will be practically no break or intermission in the continuity of the display of pictures as one film runs out and another is to be started immediately following the running out of the first film; and the invention has the further object of providing an apparatus that not only acts automatically but is reliable and comparatively inexpensive and can be readily organized with apparatus of this kind in course of construction 20 of the same and can also be readily applied to apparatus already constructed and also in use; and the invention consists of the features an embodiment of which is illustrated in the accompanying drawings and 25 described and claimed herein.

Figure 1 is a side elevation of one of two connected motion picture projecting apparatuses of any well-known type, a portion of the apparatus being broken away to show 30 details of construction.

Fig. 2 is a detail sectional elevational view on line 2—2 of Fig. 1 showing one type of dowser controlling switch.

Fig. 3 is a section on line 3—3 of Fig. 2 40 looking at right angles to the plane of Fig. 2.

Fig. 4 is a detail side elevation of a portion of a film reel showing a part of the circuit control mechanism mounted thereon.

Fig. 5 is a side elevation of a portion of the film operating mechanism partly broken away to indicate means for operating the dowser switch.

Fig. 6 is a diagrammatic view showing the 50 wiring system connecting two sets of motion picture apparatus or machines in which the present invention has been incorporated.

Fig. 7 is a detail sectional elevation substantially longitudinal of a solenoid and its 55 casing and showing in elevation a dowser

connected thereto and disposed in relation to the cone of the lantern box, the cone being sectioned on line 7—7 of Fig. 1.

Fig. 8 is a side elevation of a portion of the cone, the latter being slightly broken 60 away and showing the dowser attachment thereon.

Fig. 9 is an elevational section on line 9—9 of Fig. 1 showing the action of the motor controlling switch device.

In the projection of motion pictures it is the common practice to have a plurality of motion picture machines set in convenient relation so that as soon as one film is run off in one machine the operator may as quickly 70 as possible start the operation of another machine to continue the display or projection of pictures, especially when the pictures of the several films are related to the same subject, and thus eliminate any appreciable 75 intermission in the projection of the series, and it is for the purpose of providing the automatic cutting out of the pictures from one projecting apparatus as the film is run out and automatically initiating the projection of pictures from another apparatus that I have devised the present invention which 80 obviously may be incorporated in organization with various types of motion picture machines and apparatus and may assume 85 various forms in its practical application.

In Fig. 6 is shown a pair of projecting means including the cones C through which the beam of light from a lantern box is projected, these cones C—C being respectively 90 mounted upon two sets of machines having, for instance, motors A and B, these motors being appropriately connected as is indicated in Fig. 1 to drive the mechanism usually provided in a housing H for winding the film F from one reel R in the upper magazine M to the lower magazine M', and as the winding mechanism involves no feature of the present invention a specific description of the same is therefore not necessary 95 other than to say that such winding mechanism involves usually a governor shaft 2, Fig. 1, in which is mounted a governor 3 which, in the present case, is connected to or carries an actuating device in the form of a disk 4 designed to engage with a complementary member which may be in the form of a lever 5, which lever when the governor device assumes a given position as determined by the speed of the shaft 2, will op- 100 105 110

erate to close a circuit having contacts in the switch box 6.

The cone C of each lantern box of a given machine is provided at its outer end with a device for cutting off the beam of light emanating in the lantern box and this device preferably is in the form of a disk or closure D, as shown in Figs. 6 and 7, that is adapted to be swung down across the opening of the cone C to prevent the issue of the beam of light and thereby protecting the film until the same is moving at a sufficient rate of speed as not to be burned or ignited and also for the purpose of instantly cutting off the projection of pictures when this is rendered desirable for any cause.

As shown in Figs. 7 and 8, the dowser plate or disk D is mounted on the lower end of a lever 10 that is mounted on a pivot rod 20 or stem 11 swinging freely in a bearing 12 mounted on a clamp ring 13 encompassing the outer end of the cone C. The dowser D is preferably counterbalanced or so constructed that it will remain substantially stable either in the closing position, Figs. 1 and 7, or in the open position as shown at the right in the diagram, Fig. 6, in the latter position permitting the free passage of beam of light from the lantern.

One of the important features of my present invention is to provide for the automatic starting of the driving motor of one machine and at the same time, substantially, actuating a suitable means that will swing one dowser D to a closed position across the cone C of its machine while the corresponding dowser D of the other machine will be thrown to the open position, the opening of the dowser occurring substantially concurrently with the starting of the motor of its respective machine; it being immaterial that the motor of the other machine in which the dowser has been thrown to closing position continues to operate for a short time so long as the projection of pictures by the apparatus is prevented when the other apparatus begins projecting.

To secure the automatic starting of the motor of one machine, as for instance the motor B, in Fig. 6, and simultaneously close the dowser D of the machine having the motor A and actuating the dowser D of the machine having the motor B to be started so as to uncover the cone opening, suitable wiring is provided and in this case is as follows:

A main feed wire 15 is provided with a branch 15^a connecting with one pole of the motor A and it is provided with a second branch 15^b connecting with one pole of the motor B. From the opposite pole of the motor B is led a branch or wire 16^b which is extended over to the other machine, carrying the motor A, and in this wire there is provided a means or motor switch B' from

which extends a wire 17^b that is connected at 18 to a feed wire 19 so that when the motor switch B' is closed by the automatic action of means provided for that purpose then a circuit will have been completed 70 through the motor B and operation of the respective machine started.

In a similar way the motor A has a return wire 16^a led to the other machine, that is the machine with the motor B, and this wire 75 16^a is provided with a main motor switch A' from which is extended a connecting wire 17^a also joined at the contact 18, for instance into the main feed wire 19. Therefore, it will be seen that when one of the 80 machines is running, as for instance the machine with the motor A, then upon a predetermined time if the switch B' thereon be thrown to closed position, as in Fig. 6, then a circuit will be completed through the motor 85 B and its respective machine operated. Conversely, if the machine with the motor B is operating then upon a predetermined time the main motor switch A' will be closed and the circuit diverted to the motor 90 A of the other machine and it will be started. The motor switches A' and B', are preferably of a construction to make only instantaneous contacts, as are also the switches 95 for actuating the dowsers D, to be herein-after explained, and therefore, any suitable form of magnetic starting device may be used in connection therewith for starting the motors and maintaining a properly closed circuit during operation.

Manifestly, diverse means may be employed for throwing the motor switches, and in this case there is mounted on the reels R that are placed in the upper magazine M, for instance, a rock shaft 20 journaled in 105 suitable bearings 21, the shaft being disposed across an opening 22 such as usually found in the side plates of ordinary reels or which opening may be especially provided if desired, and through this there is 110 normally projected the inturned end of a lever 23, Figs. 4 and 9, this inturned end being normally positioned at such a location with respect to a film wound on the reel that at a suitable time in the unwinding 115 of the film the lever or finger 23 will be freed from the film and swung or permitted to move to the dotted line position, Fig. 9, this movement being accomplished as by a spring 24 wound around the rock shaft 20 120 and fixed at one end so as to react to rock the shaft with the finger in the desired direction.

The finger 23 having been released by the unwinding film F is adapted to project so 125 that during the rotation of the reel R the finger or portion thereof will engage a tap-pet lever 25, Figs. 1 and 9, disposed on a pivot or rock shaft 26 that is journaled at 27 130 in the side of the magazine M, and on the

outer end of the pivot shaft 26 is attached another lever 28 to the swinging end of which is connected a push rod or trigger 29.

Assuming that the trip mechanism just described is mounted on the machine having the motor A, Fig. 1, this trip rod 29 is designed to actuate the switch B' for controlling the circuit of the motor B on the other machine of the combination. The switch B' is preferably of the same construction as shown in Fig. 2, and is shown as mounted on the side of the upper magazine M in a box 30 in which are provided the contacts for the wiring 16^b and 17^b so that when the push rod 29 throws the switch on B' a circuit is completed at the contacts of the terminals in the switch box and the motor B thus started. Obviously a similar organization is arranged on the machine having the motor B so that at a desired period in the unwinding of a film from the magazine M the complementary motor switch A' of the other machine will be likewise operated.

Having thus above provided for the automatic starting of the motor of one of the machines, it is desirable to provide for the simultaneous closing of one dowser and opening of the other and this is accomplished in one embodiment of the invention through a device above referred to including the governor 3 and the actuating member 5 which is provided to throw a switch located in the switch box 6 one for each machine.

Each switch box 6 is provided with a switch arm 35 of any suitable construction and appropriately mounted, as for instance on a pivot shaft 36, Figs. 2 and 3, the ends of the switch arm 35 being adapted to engage respective contacts 37 and 38 from which lead respectively a wire 37^a which is connected to the feed wire 19 as at 39, the contact 37 being connected to a wire 40 having one branch 41 extending into a duplex solenoid, one coil of which is indicated at 42 and one end of which is connected to a common wire 43 which is connected at 44 to the main feed wire 15 so that a circuit is closed through the main feed wire 15, branch 43, coil 42, return 41 to the wire 40 with its contact 37. There is also connected to the wire 40 another branch 45 that extends to the other machine and is attached to one terminal of one coil as 46 also forming a part of another duplex solenoid; the coils of which are, at the adjacent ends, connected to a common return wire 47 leading into the main wire 15^a.

Connected to the common wire 43 of the solenoid coil 42 there is a similar coil 42^a from which leads a wire 50 extended to the machine having the motor B and connected to a terminal of the switch 35 of said machine, and from this same terminal extends a conductor 51 that is attached to the opposite end of a coil 46^a coördinate to the

coil 46 of the same solenoid, the other end of the coil 46^a being connected to the common wire 47. Current is supplied to the wires 50 and 51 when the adjacent switch 35 is closed to make contact with a terminal of a branch 37^b connected as at 39 to the main feed wire 19. From the above it will be seen that I have provided a duplex solenoid on the machine having the motor A the solenoid including coils 42 and 42^a and I have also provided a duplex solenoid on the machine with the motor B having coils 46 and 46^a.

These duplex solenoids operate in similar manner and are respectively connected to dowsers D on their machines. A suitable method of connection in an embodiment of the invention is shown in Figs. 7 and 8 in which the coils 42 and 42^a of a solenoid are mounted in a suitable casing 52 in the ends of which are arranged adjusting screws 53 which may be provided with bumpers 54 on their inner ends that extend into the sleeve of the solenoid and in which there operates a core 55 one end of which is provided with a rod 56 passing through an end of the casing and through one of the adjusting screws 53, the outer end of the rod 56 being provided with a cross pin 57 on which is mounted a pivoting block 58 sliding in a bifurcated or slotted arm 59 that is attached to a convenient portion of the pivot or rock shaft 11 of the respective dowser D.

Therefore, upon the closure of the switch 35 of a respective solenoid with the dual coils the excited coil will cause a longitudinal movement of the core 55. As for instance if the coil 42 is energized then the core 55, Fig. 7, is thrown to the position shown with the result that the dowser is set across the end of the cone C to cut off the beam, and, conversely, when the control switch 35 on the other machine is thrown so as to energize the coil 42^a the core 55 is shifted reversely or to the opposite end of the coil in Fig. 7 and the dowser D is swung to a position indicated at the right of Fig. 6.

The dowser controlling switches 35 are respectively operated on the different machines when the coupling or actuating member 5 thereof is shifted by the action of the governing device 3, this transmitting member 5 being designed to engage with a push rod 5', Figs. 2 and 3, extending into the casing 6 and normally resting against a contiguous portion of the switch arm 35, the latter being shown as having a supporting shoulder 35^a on which the end of the rod 5' normally rests when the switch arm 35 is thrown to the upright position under the action of a return spring 35^b surrounding the pivot pin or stud 36.

As the push rod 5' is thrust against the adjacent end of the lever 35 the latter is tilted to the dotted line position, Fig. 2, and

the end of the rod 5' slips off of its support 35^a and permits the spring 35^b to return the switch arm 35 to a circuit breaking position shown in full lines. When the switch arm 5 35 is thrown to the dotted line position the circuit is closed through the contacts 37 and 38. This momentary completion of a circuit by the given switch 35 is sufficient to excite respective coils of the duplex solenoids so that the positions of the dowsers D 10 are simultaneously reversed.

The operation of my invention as a whole is as follows:

Assuming the projector operated by the 15 motor A to be projecting a picture; when the picture film reaches its end, the switch B' is closed by the disengagement of the arm 23 from said film, through the medium of the arm 25, shaft 26, arm 28 and push rod 29 of said projector, whereupon the motor B of the other projector is operated, the current passing through main 15, lead 15^b, motor B, lead 16^b, switch B', lead 17^b and main 19. When the shaft 2 of said other 20 projector, which is driven by the motor B', reaches a predetermined speed, the switch 35 of said projector is closed by the governor 3 thereof, whereupon the coils 42^a and 46^a are energized and the dowsers D of the 25 projectors driven by motors A and B are respectively closed and opened, the current passing through main 15, lead 43, coil 42^a, lead 50, switch 35, lead 37^b and main 19, and through main 15, lead 15^b, lead 47, coil 30 46^a, lead 51, switch 35, lead 37^b and main 19, as shown in heavy lines in Fig. 6.

When the film of the projector operated by the motor B reaches its end, the switch A' is closed by the disengagement of the arm 40 23 from said film, through the medium of the arm 25, shaft 26, arm 28 and push rod 29 of said projector, whereupon the motor A of the first projector is operated, the current passing through main 15, lead 43, lead 15^a, motor A, lead 16^a, switch A', lead 17^a and main 19. When the shaft 2 of said first projector, which is driven by the motor A, reaches a predetermined speed, the switch 45 35 of said projector is closed by the governor 3 thereof, whereupon the coils 42 and 46 are energized and the dowsers D of the projectors driven by motors A and B are respectively opened and closed, the current passing through main 15, lead 43, coil 42, 50 lead 41, lead 40, switch 35 of said projector, lead 37^a and main 19, and through main 15, lead 15^b, lead 47, coil 46, lead 45, lead 40, switch 35, lead 37^b and main 19 as shown in light lines in Fig. 6.

Various changes may be made without departing from the spirit of my invention as claimed.

I claim:

1. Motion picture apparatus having, in 55 combination, a plurality of motion picture

machines with a motor for each, a dowsers for each machine, and means for automatically closing the dowsers of either machine and opening the dowsers of the other and for starting the motor of the machine on which the dowsers is opened.

2. Motion picture apparatus having, in combination, a plurality of motion picture machines with a motor for each, a dowsers for each machine, and electromagnetic means 75 for automatically closing the dowsers of either machine and opening the dowsers of the other and for starting the motor of the machine on which the dowsers is opened.

3. Motion picture apparatus having, in 80 combination, a plurality of motion picture machines each with a dowsers device to control the passage of light to films in the machines, motors for the respective machines, and film controlled means for 85 reversing the positions of the said devices to control projection of pictures.

4. Motion picture apparatus having, in combination, a plurality of motion picture machines with a motor for each, a dowsers for each machine, and film controlled means 90 for automatically closing the dowsers of either machine and opening the dowsers of the other and for starting the motor of the machine on which the dowsers is opened. 95

5. A motion picture apparatus having, in combination, a plurality of projection machines, dowsers for each machine, a motor for operating each machine, a film controlled means on each machine for starting the motor of the other machine, and speed controlled means on each machine for simultaneously actuating the dowsers to close one as the other opens.

6. A motion picture apparatus having, in 105 combination, a plurality of projection machines, dowsers for each machine, a suitable motive power for actuating the machines, film controlled means on each machine for operatively connecting the other machine 110 with its motive power, and speed controlled means on each machine to simultaneously actuate the dowsers, to close one as the other opens.

7. A motion picture apparatus having, in 115 combination, a plurality of projecting machines, a dowsers pivotally mounted on each machine to control the projection of light to the films, a motor for operating each machine, electro-magnetic means for actuating 120 said dowsers to alternately open and close the light apertures, a speed controlled switch on each machine for closing circuits to simultaneously actuate the dowsers actuating means, and film controlled switches on 125 each machine for closing circuits to operate the motor on the opposite machine.

8. A motion picture apparatus having, in combination, a plurality of projecting machines, dowsers to control the light on each 130

machine, a suitable motive power for actuating the machines independently of each other, film controlled means on each machine for independently starting the motive power 5 of the other machine, and speed controlled means on each machine for simultaneously actuating the dowsers to open the one on the machine just starting and closing the other.

9. A motion picture apparatus having, in 10 combination, a plurality of projecting machines, dowsers over the light apertures on each machine, a suitable motive power for actuating the machines independently of each other, film controlled means on each 15 machine for independently connecting the machines with their motive power, and speed controlled means on each machine for simultaneously actuating the dowsers to cover one light aperture and uncover the other, said 20 last mentioned means adapted to be actuated by the initial starting of its machine when it has acquired a predetermined speed.

10. A motion picture apparatus having, in combination, a plurality of projecting machines, dowsers for the light apertures in 25 each machine, electro-magnets for actuating said dowsers to alternately cover and uncover the light apertures, motors to operate each machine independently of the other, film controlled means on each machine for 30 independently starting the motor of the other machine, and speed controlled means on each machine for simultaneously actuating the dowsers actuating means, said speed controlled means each being adapted to be 35 actuated by the initial starting of the machine on which it is mounted when it has attained a predetermined speed, to uncover the light aperture on such machine and cover the light aperture on the other. 40

In testimony whereof I have signed my name to this specification.

F. E. WEAVER.
